UNITED STATES PATENT OFFICE.

WILLIAM J. MEIER, OF LANSING, MICHIGAN.

CHIMNEY.

Application filed June 16, 1925. Serial No. 37,553.

This invention relates to chimneys, and more directly to ventilating chimneys, and belongs to that class of structures for the same purpose, in which are formed upwardly and inwardly inclined air channels through which moving external air may enter and be caused to flow upwardly in the flue thereby materially aiding the draught of the chimney while preventing down draught.

The object of this invention is the production of a chimney of the character stated, which is made up of separate parts each of which is removable. A chimney constructed in accordance with this invention may be erected "dry". That is to say, no mortar need be used, and the whole can be as easily taken down for the renewal of all or any broken part. A manufacturer of chimneys made as herein set forth is able to furnish them in knock-down condition, each part being usually made of cement or the like, and the whole to be assembled on the job, as the blocks or members fit into place making a very rigid chimney without using mortar, and which can readily be repaired by replacing any one of the members without upsetting the entire chimney.

The various parts of this invention are of special construction and arrangement, and the forms and disposition thereof are illustrated in the accompanying drawings of which Fig. 1 represents a side view of all parts assembled, the near left hand corner of the chimney being broken away to disclose interior members. Fig. 2 is a side view of one of the vanes by itself. Fig. 3 is an edge view from the top or beveled edge portion of the vane. Fig. 4 is a cross-section of one of the corner uprights taken on the broken line 4-4 of Fig. 1. Fig. 5 is a top view of one of the corner block members which are all alike.

Throughout the drawings and description the same number is used to refer to the same part.

Considering the drawings, on a brick or other kind of base 1, are standing four corner uprights 2 in vertical position and all alike. On adjoining faces each has the L-shaped downwardly and outwardly extending grooves 3 and 4. While L-shaped grooves are shown in the drawings, it will be understood that dovetail grooves may be used as well. Engaging the grooves are vanes 5. Each vane has the side flanges 6

constructed to enter the grooves, and each vane has a narrow edge or top 7 terminating a beveled surface 8.

The chimney top is made up of four corner pieces or blocks 9. Each has a side extension 10 with a dovetail recess 11, and a second side extension 12 on the adjoining side provided with a like dovetail recess 13. It may be here stated that if it is desired the top blocks may be provided with dovetail seats 14, and an additional chimney cap or top fastening can be employed, not shown in the drawings.

Considering Fig. 1, one of the intermediate blocks 15 is shown in detail. Each intermediate block has on opposite sides the cavities 16, and the downwardly projecting dovetail lug 17. It will also be noted that the lower and inner corner of the intermediate block 15 is given an inclined surface 18 downwardly and outwardly. It will be further noted that the surface 18 is the upper wall of the upper air channel of the chimney. Each of the side extensions 10 and 12 of the corner blocks 9 are provided with surfaces having the same inclination as 18, and in Fig. 1 it will be noted that the uprights are given a pyramidal form at the top such as the top end 19 of the upright 2. In other words, the two meeting sides of each upright that form the outer corners of the chimney are cut away at the top as illustrated in Fig. 1 showing one side of the pyramidal top end of the upright, that end being marked 19.

When the various parts are assembled, the flue 20 of the chimney is substantially unbroken, the beveled surfaces 8 of the vanes being presented inwardly and vertically. The corner blocks 9 and intermediate blocks 15 form the chimney top. It will be understood that the corner blocks may be placed in position on any plane support, and the intermediate blocks passed downwardly between the corner blocks, whereupon the dovetail lugs such as 17 engage the corresponding seats such as 11 in the extension of the corner block, and the chimney top then constitutes very rigidly one piece. It may be raised and set down upon the pyramidal top ends of the associated uprights and vanes, and by its weight and construction it not only secures the uprights in place and itself in position thereon, but the corner blocks and intermediate blocks are additionally secured by reason of the wedge action of the

pyramidal tops of the uprights, and by the fact that the lugs 17 are dovetail devices. It will be understood that no mortar is used in this assembly, and that a variety of changes may be made in the exterior forms of the members within the scope of this invention.

Having now described this invention and its operation, I claim:—

- 10 1. In a chimney, the combination with corner uprights each having on adjoining faces downwardly and outwardly inclined grooves, of vanes provided with side flanges constructed to engage the grooves of the uprights thereby affording upwardly inclined air channels between them, and a chimney top formed of separable members constructed to engage each other and to engage the said uprights, the said uprights and chimney top having upwardly and inwardly inclined portions in contact whereby the weight of the top exerts an inward pressure on the uprights.
- 15 2. In a chimney, the combination with cor-

ner uprights, of removable vanes, the said uprights and the said vanes being provided with devices mutually engaging each other and securing the uprights and vanes together in detachable relation whereby the uprights are held against separation in the direction of the length of said vanes, a chimney top having corner pieces and intermediate pieces, the said corner and intermediate pieces having means carried by them for securing them removably together, and the said chimney top being constructed to engage the said uprights.

3. In a chimney, the combination with corner uprights, of removable vanes arranged between the uprights, the said uprights having pyramidal top ends, a chimney top constructed with separable corner pieces having internal inclined surfaces arranged to engage the said pyramidal top ends of the uprights whereby the said chimney top is retained in place.

In testimony whereof I affix my signature.
WILLIAM J. MEIER.
